RESISTANCE DEVICE AND UNIT THEREFOR

Donald F. Hastings, Fairlawn, N. J., assignor to
Hardwick, Hindle, Inc., Newark, N. J.

Application January 9, 1934, Serial No. 705,869

5 Claims. (Cl. 201—63)

This invention relates to an improved form of resistance device and unit therefor.

While I am aware that resistance units and devices have been made in many ways, yet I believe the structure shown and described herein includes a number of advantages not present in prior art devices with which I am familiar.

It is one of the objects of my invention to produce a compact wire-wound resistance unit of relatively high resistance value.

Another object of my invention is to produce a compact wire-wound resistance unit which will dissipate a relatively large amount of power.

Another object of my invention is to provide a resistance unit which can be easily and cheaply made, yet one that is rugged in construction and will therefore stand much abuse in handling and in operation.

A further object of my invention is to provide a new type of resistance unit which may be assembled in groups to make up a resistance device which will take up a minimum amount of space, yet which will have a high wattage rating due to the large radiating surface with respect to volume attained by my construction.

These and other objects will be apparent to one skilled in the art of constructing resistances, after reading the specification taken in connection with the annexed drawing, wherein:

30 Figure 1 is a plan view of one of my resistance units without the outer covering applied thereto.

Figure 2 is a longitudinal section on the line 2—2 of Figure 1, but with the outer covering in position.

35 Figure 3 shows a resistance device composed of a number of the individual units as shown in Figures 1 and 2.

Figure 4 is a plan view of a modified form of plate which may be used as a terminal and binding plate.

Figure 5 is a section on the line 5—5 of Figure 4.

Figure 6 is a plan view of one form of resistance winding which may be utilized in the construction of the complete unit.

Figure 7 is a diagrammatic illustration showing the manner in which the resistance winding of Figure 6 may be assembled between the binding and terminal plates.

50 Figure 8 is a view somewhat similar to Figure 5, showing a different way of making contact with the terminal plate of the resistance unit.

Figures 9 and 10 show modified forms of terminal and binding plates.

In the various views, 1 and 2 are flat metallic plates preferably of soft copper for the reason that copper is a very good conductor of heat and such plates will act to quickly collect and dis-

tribute the heat over the surface of the unit.

whereby the heat from the winding is rapidly dissipated. Between the plates 1 and 2 there is located a resistance winding 3 wound on a flat form 4 of heat-resisting material such as a sheet of mica. The plate 1 is prevented from contacting with the turns of the winding 3 by an insulator 5, and likewise, the turns of the winding 3 are prevented from contacting with the plate 2 by an insulator 6. The insulators 5 and 6 are preferably of good heat-resisting material such as mica.

To hold the plates 1 and 2 in position over the insulators 5 and 6, and the resistance winding 3, the plate 2 is provided with fingers 7 and 8 which are bent upwardly and lie on the insulator 5, leaving a space 11 which is provided by notching out the corners of the plate 1. Likewise, fingers 9 and 10 are positioned on the bottom side of the unit in a similar manner. The plate 1 is provided with a terminal extension 12 and the plate 2, with a terminal extension 13. The extensions 12 and 13 may be each provided with an eyelet 14 which also serves to clamp the ends of the winding, one end 15 being shown, as each eyelet is spun or stamped into locking position on the terminal.

Preferably, each of the plates 1 and 2 has a raised portion 16 for the purpose which will be hereinafter pointed out.

After what might be considered a stack has been completed as shown in Figure 1, the unit is then provided with an outer coating 35 of vitreous enamel, with the exception of the raised portion 16 and that portion of the terminals 12 and 13 around the eyelets 14. The enamel bridges over the spaces 11 and completely seals the whole unit, thus rendering the same substantially moisture-proof. After the units are completed as above described, they may be assembled in any satisfactory manner by use of the eyelets 14 which may also be used for making connections to the terminal plates and hence to the extremity of the resistance winding.

In addition, the units may be assembled as shown in Figure 3 by stacking a plurality of units in a substantially mechanical, parallel relationship, whereby the raised portion of one unit is in contact with the raised portion 16 of the next adjacent unit, and these units may be held in assembled relation in any satisfactory manner as by a mounting composed of a base 17, preferably of insulating material, having metallic upright supports 18 and 19, one of which, such as 18, carries a clamping screw 20 for clamping the units in position and also for making electrical connection through the units from the terminal binding post 21 to the binding post 22.

By reference to Figure 3, it will be seen that the resistance units may be of different ohmic

- resistance and any one of the units may be used independent of the others by connecting the terminal wires directly to the terminals 12 and 13 of the unit desired, instead of to the binding 5 posts 21 and 22; or one side of the circuit may be connected to both the binding posts 21 and 22 and the other circuit wire connected to any one of the terminals 12 and 13 of the different units, thereby giving a series parallel arrangement 10 of the resistance units. In addition, one side of the circuit may be connected to either one of the terminals 21 or 22, while the other side of the circuit may be connected to any one of the terminals of the various units, thereby providing 15 what is generally referred to as a tapped resistor.

In Figure 4, I have shown a terminal and binding plate 1 with the binding lugs 9 and 10 and raised portion 16 as in Figure 1, but the terminal 20 12 may be provided with an integrally formed eyelet 23 around which one terminal end of the resistance wire 24 may be wound, and then the eyelet 23 is spun over or forced into position to clamp the wire 24. While I have shown an integral eyelet 23, it is to be understood that a 25 separate eyelet may be used at this point if desired. This construction leaves a hole 25 in the terminal 12 for ease in soldering a connecting wire thereto, or for mounting purposes, in which 30 case the terminal wire may be wound around the terminal 12 at the V-shaped junction point 26.

Instead of a single form 4 carrying the resistance winding 3, I may use a plurality of 35 windings 3 all wound on a unitary form 27 which has slots 28 punched therein before the winding 3 is applied thereto as shown in Figure 6.

By constructing the form 27 in the manner just described, the form may be readily folded 40 up on the line of the slots 28 as shown in Figure 7, without any danger of breaking the winding at these bendable points, insulators 29 being utilized between the various windings 3 of the unit structure. After the form has been folded up as 45 shown in Figure 7, the extremities of the winding are connected to the plates 1 and 2 which are applied and fastened in position as has been described.

In certain cases, the raised portion 16 may 50 having a binding post 36 fastened thereto as in Figure 8, whereby connection may be made to the unit instead of in the manner previously described.

In Figures 9 and 10, I have shown modified 55 forms of the terminal and binding plates 1 and 2. In Figure 10, the plate 1 is provided with four bendable fingers 31 which are adapted to be clamped over the stack and into the spaces 32 provided on the plate 2 as shown in Figure 9, it 60 being understood that the fingers 31 and the spaces or notches 32 are such that the fingers 31 will not touch any portion of the plate 2. This construction tends to prevent any weaving of the plates 1 and 2 during the handling operation 65 leading up to the enameling of the units.

In some cases, I may use the side fingers 33 which are indicated by dotted line in connection 70 with the plate 1, and these fingers are adapted to be positioned in clearance notches 34 indicated by dotted lines in Figure 9.

From what has been said, it will be understood 75 that the type of resistance unit herein shown and described, will radiate a considerable amount of heat; that is to say, the wattage rating of the unit is relatively high. This feature is especially

useful when the units are arranged in a compact space as illustrated in Figure 3. Furthermore, the construction of the unit is such that if one should burn out in an arrangement such as shown in Figure 3, this unit may be readily 5 and quickly replaced by a new unit.

While I have shown a series of sections wound on a single bendable form 27, as in Figure 6, it is to be understood that a number of individual sections as shown in Figures 1 and 2 may be 10 stacked between the binding plates 1 and 2, and these different sections may be connected in series or parallel as desired.

What I claim is:

1. A resistance unit including a relatively thin 15 and flat core of heat-resisting insulating material, a winding on said core, insulators of heat-resisting material positioned on opposite sides of said winding, and metallic binding and terminal plates positioned on and overlying the faces of 20 the opposite sides of the unit against said last-mentioned insulators, said plates being provided with means for locking themselves in position over said insulators, and means on each plate for connecting an end of the winding securely there- 25 to, said unit having an outer covering of baked vitreous enamel.

2. A resistance unit as set forth in claim 1, characterized in that the central part of each of 30 said plates has a raised uncovered portion for the purposes described.

3. A resistance device consisting of a relatively 35 flat stack of elements including a pair of metallic binding plates having portions bent over the stack to form a self-lock and also having terminal 40 projections, a resistance winding positioned between but insulated from said plates, said winding being wound on a single elongated flat form of heat-resisting material having connected but foldable sections, that part of the winding on 45 one section being separated by a suitable insulator from the next adjacent section winding when the sections are folded up for placement between said metallic plates, and an outer covering of baked vitreous enamel over the whole device 45 except at least the ends of the terminal projections.

4. A resistance device including a mounting 50 having circuit terminals, said mounting carrying a plurality of resistance units, each unit including a flat stack of elements and a pair of metallic binding plates having self-locking portions extending over opposite sides of the stack and also having terminal projections, and at least one 55 resistance winding wound on a flat form to lie between but insulated from said plates, the ends of the winding being connected between said plates, each plate having an integral flat raised portion to engage a similar raised portion of another unit whereby the units are normally 60 connected in series, and each unit being covered with a baked vitreous heat-resisting material except for said raised portions and the ends of said terminals.

5. A resistance device including a plurality of 65 resistance units as defined in claim 4 in which the units are arranged in mechanical parallel relationship with the central uncovered portions in contact, means being provided for holding said units in said position whereby the units may be 70 readily connected in series or series parallel relationship, or any one of the units may be used separately, or the units may be used or connected as a tapped resistor.
